UNITED STATES PATENT OFFICE

164,487

CHAIR

Aaron S. Goldberg, Philadelphia, Pa., assignor to
 Bunting Glider Company, Philadelphia, Pa., a
 corporation of Pennsylvania

Application November 4, 1947, Serial No. 142,292

Term of patent 14 years

(Cl. D15—1)

To all whom it may concern:

Be it known that I, Aaron S. Goldberg, a citizen of the United States and a resident of Philadelphia, county of Philadelphia, State of Pennsylvania have invented a new, original, and ornamental Design for a Chair, of which the following is a specification, reference being had to the accompanying drawing, forming a part thereof, wherein:

Figure 1 is a front perspective view of a chair, showing my new design;

Figure 2 is a rear perspective view thereof;
 Figure 3 is a side elevational view thereof; and
 Figure 4 is a front elevational view thereof.

I claim:

The ornamental design for a chair, as shown.

AARON S. GOLDBERG.
